UNITED STATES PATENT OFFICE.

JOHN A. SCOTT, OF ST. LOUIS, MISSOURI.

CAN PUNCTURING AND SEALING DEVICE.

1,370,921.

Specification of Letters Patent.

Patented Mar. 8, 1921.

Application filed August 2, 1919. Serial No. 315,017.

To all whom it may concern:

Be it known that I, JOHN A. SCOTT, a citizen of the United States, residing at the city of St. Louis, State of Missouri, have 5 invented a certain new and useful Improvement in Can Puncturing and Sealing Devices, of which the following is a full, clear, and exact description, such as will enable others skilled in the art to which it apper- 10 tains to make and use the same, reference being had to the accompanying drawings, forming part of this specification.

My invention relates to new and useful can puncturing devices, and particularly to 15 a device utilized for puncturing and sealing cans that serve as containers for liquid products such as milk, syrup, paint and the like; the principal object of my invention being to provide a relatively simple one- 20 piece device which can be easily and quickly inserted through the walls of a can, or like container, and which device can be readily manipulated so as to uncover and close the opening through which the liquid 25 contents of the can are discharged.

With the foregoing and other objects in view, my invention consists in certain novel features of construction and arrangement of parts hereinafter more fully described 30 and claimed, and illustrated in the accompanying drawings, in which—

Figure 1 is a perspective view of the can puncturing and sealing device of my improved construction.

Fig. 2 is a vertical section taken through the upper portion of a can showing my improved device inserted through one of the walls or one side thereof.

Fig. 3 is a sectional view similar to Fig. 40 2, showing the device inserted through oppositely disposed walls of the can or container.

Referring by numerals to the accompanying drawings, which illustrate a practical embodiment of my invention, 10 designates the main body portion of the device, which is preferably constructed of metal and in the form of an elongated cylindrical shank. One end of this shank is pointed, as designated by 11, and the opposite end is provided with an integrally formed plate or arm 12 that extends a substantial distance laterally from the axis of the shank. A portion of the shank 10 immediately adja-

cent to the plate or arm 12 is tapered so 55 that it gradually increases in diameter toward said arm or plate 12, and this tapered portion is externally threaded, as designated by 13. The thread formed on this tapered portion is preferably of the quick acting 60 type, that is, it has a rather sharp pitch, so that in operation it will effect a substantially lengthwise movement of the device with a relatively small rotary movement.

To use my improved device, the pointed 65 end 11 of the shank is applied to the outer face of one of the walls of the can or container and by applying pressure to the plate or arm 12, said pointed end will be forced through the wall of the can, and by con- 70 tinuing the pressure upon the outer end of the device, the shank will be forced entirely through the can until the pointed end 11 bears upon the inner surface of the opposite wall of the can. When so positioned, the 75 inner end of the threaded portion of the shank lies immediately adjacent to the wall of the can or container through which the pointed end of the device was first inserted, and the operator may now either apply suffi- 80 cient pressure to the plate 12 to cause the pointed end of the shank to puncture the opposite wall, or by simultaneously rotating the device and applying inward pressure thereto, in which event the thread 13 will 85 coöperate with the wall of the can around the first opening and thus exert force to cause the pointed end of said device to pass through the opposite wall of the can. Thus an opening is provided through which the 90 contents of the can may be discharged when the latter is tilted or turned on its side.

To unseal this opening and effect a discharge of all, or a portion of the contents of the can, the plate or arm 12 is engaged 95 and turned so as to unscrew the threaded portions 13 of the device from the wall of the can in which it is seated, such action retracting or withdrawing the pointed end of the device from the outlet opening, 100 thereby permitting the passage of the contents of the can through said opening.

To effectually seal the can, it is only necessary to rotate the device by engaging the plate or arm 12 so as to screw the threaded 105 portion 13 into the wall with which it is engaged, and such action positions the pointed end 11 of the device in the dis-

charge opening (see Fig. 3). It will be understood that the arm or plate 12 performs the functions of a crank arm to rotate the device while it is being screwed 5 into or out of the can, and such crank arm is effective in obtaining increased leverage for effecting the rotary movement.

A can puncturing and sealing device of my improved construction is comparatively 10 simple, can be easily and cheaply manufactured, and is very effective in performing its intended functions.

It will be readily understood that minor 15 changes in the size, form and construction of the various parts of my improved can puncturing and sealing device may be made and substituted for those herein shown and described, without departing from the spirit of my invention, the scope of which is set 20 forth in the appended claims.

I claim:

1. A can puncturing and sealing device comprising a straight smooth body portion, one end of which terminates in a smooth tapered point, the opposite end of said body 25 portion being screw-threaded, and means secured to the threaded end of said body portion for manipulating the same when it is inserted into a can.

2. A can puncturing and sealing device 30 comprising a shank having a straight smooth body portion, one end of which terminates in a smooth tapered point, the other end of said shank being screw-threaded, and an arm projecting laterally from the 35 screw-threaded end of the shank.

In testimony whereof I hereunto affix my signature this 26th day of July, 1919.

JOHN A. SCOTT.
